10 Claims

ABSTRACT OF THE DISCLOSURE

An integral ceiling having an access panel is supported by a grid system including main and cross beam members, the access panel includes two panel segments supporting for freely pivoting upwardly from below to an open position, a pair of locking members carried on the end of one segment to hold down the other segment and are slidable laterally into openings in the cross beams members to lock the access panel in closed position, said locking members are hidden but accessible from below the panel to selectively lock and release the panel without interrupting ceiling decor.

BACKGROUND OF THE INVENTION

The present invention relates to a grid for supporting ceiling panels from an overhead structure and particularly to a releasable holdown arrangement for an access panel forming a part of an integral suspended ceiling.

It is known to provide suspended ceilings comprising panels supported by a grid of interlocking beams, wherein the supporting grid is concealed. Such ceilings have an enhanced appearance as contrasted with suspended ceilings where the supporting grid is exposed.

However, such concealed systems require special provisions for gaining access to the space thereabove. It is known to provide access panels in concealing ceiling systems which can be swung upwardly from below. However, these pose a problem when the ceiling is to be fire-rated, because of the fear that such freely movable access panels may destroy the requisite integrity of the ceiling.

SUMMARY OF THE INVENTION

It is a primary object of this invention to provide an access panel in a concealed suspended ceiling wherein the ceiling integrity is maintained.

It is another object of this invention to provide an access panel in an integral suspended ceiling having a grid supporting a plurality of ceiling panels with means releasably locking the access panel in closed position flush with adjacent ceiling panels providing a smooth, continuous ceiling surface and uninterrupted ceiling decor.

A further object of the invention is to provide the foregoing characteristics in a locking arrangement hidden above the exposed ceiling surface but accessible from below the ceiling to lock and unlock the access panel without interrupting the decor of the ceiling surface.

BRIEF DESCRIPTION OF THE DRAWINGS

FIG. 1 is a fragmentary perspective view of the upper side of an integral suspended ceiling illustrating in partially opened position an access panel constructed in accordance with the present invention;

FIG. 2 is an enlarged, fragmentary cross sectional view thereof taken about on line 2—2 of FIG. 1 with the access panel in closed position and with parts broken out for ease of illustration;

FIG. 3 is a fragmentary cross sectional view thereof taken about on line 3—3 of FIG. 2 with parts broken out for convenience in illustration;

2

FIG. 4 is an enlarged, fragmentary cross sectional view of the partially opened access panel taken about on line 4—4 of FIG. 1; and

FIG. 5 is an enlarged, fragmentary, cross sectional view of a portion of the suspended ceiling taken about on line 5—5 of FIG. 1.

DETAILED DESCRIPTION OF THE PREFERRED EMBODIMENTS

Referring to FIG. 1, there is illustrated a portion of a suspended ceiling having a supporting grid generally comprising spaced, parallel main beam support member 10, a plurality of spaced cross support members 11, 11' extending at right angles to and supported by and between main support members 10, and a plurality of auxiliary support spline members 12 extending parallel to main support members 10 between adjacent cross support members 11 and 11'. The support grid is adapted for suspension from an overhead structure by wires or other conventional means, not shown, in a manner understood in the art. Member 10, 11, 11' and 12 are formed to support ceiling panels 13 in a manner to afford a rigid, integral suspended ceiling having a continuous, uninterrupted exposed ceiling surface through which an access panel, generally designated 14, is provided. It will be understood that the ceiling comprising grid members 10, 11, 11' and 12 and panels 13 may extend to any length and breadth desired, and that an access panel 14 can be positioned between any pair of adjacent main support members 10 in virtually any desired location therealong.

While not limited thereto main beam support members 10 are formed in the shape of an inverted T and fabricated from a single piece of sheet material to comprise a normally vertical web portion 15 (FIG. 2) surmounted by a longitudinally extending, box-like reinforcing bead 16 and having along its bottom edge lateral flanges 17 and 18 on opposite sides thereof.

As seen in FIG. 5, cross support members 11 comprise paired support and saddle splines 19 and 20, respectively. Support splines 19 are fabricated from a single piece of sheet material to comprise a half coped spline in the shape of an L having web and flange portions 21 and 22, respectively. Connecting members are provided at the ends of support spline 19 in the form of a generally inverted J-shaped hook 23 (FIG. 2) having a pair of leg portions 24 and 25 straddling box section 16 of main support member 10. Each leg portion 24 bears on the associated main beam flange 17 or 18, as the case may be, and has an inward extension 26 riveted or otherwise secured to web 21 of its associated support spline 19 as shown at 27. Hooks 23 thereby comprise connecting members extending from the ends of cross support members 11.

Saddle splines 20 are coextensive with support splines 19. Each spline 20 is fabricated from a single piece of sheet material to comprise a generally Z-shaped cross section, as seen in FIG. 5, having a web portion 28, a lower horizontal flange 29 and an upper flange 30 inclined downwardly on the side of web 28 opposite flange 29.

Cross support members 11' are provided at opposite ends of access panel 14, and are like cross members 11 except that a pair of saddle splines 40 are provided in place of the single saddle spline 20, as will be described hereafter.

Auxiliary support members 12 preferably are formed from a single piece of thin gauge sheet material to comprise an inverted T spline having a web portion 31 and flange portions 32 on opposite sides thereof, as seen in FIGS. 1 and 5, the opposite ends of flanges 32 being cut back from the ends of webs 31 to accommodate the associated flanges 22 and 29 of the saddle and support

splines 19, 20 on which webs 31 bear when assembled, as shown in FIG. 5 and as will presently be described.

Each ceiling panel 13 is provided along each of its four lateral edges with grooves or kerfs 33 for receiving the flanges of its associated support members 10, 11, 11' and 12. Kerfs 33 divide the edges of panels 13 into upper and lower lips 34 and 35, upper lip 34 being inset from lower lip 35 to accommodate the webs of the associated support members while lower lips 35 of adjacent panels 13 have a slight clearance slot 36 therebetween when assembled.

The ceiling areas between adjacent cross support members 11, 11' and main support members 10 define panel sections A, B, C, D and E (FIG. 1) with each section, in the illustrated form, comprising four panels 13 supported by the kerf engaging flanges of the surrounding members. To form the ceiling, the lateral edges of adjacent panel sections engage paired support and saddle splines 19, 20 or 19, 40 with the saddle splines 20, 40 on opposite lateral edges of one panel section hooking over support splines 19 forming the corresponding lateral edges of the next adjacent panel sections. For example, the lateral edges of panel sections B and D engage support splines 19 whereon the lateral edges of panel sections A, C and E engage saddle splines 20, 40. Inclined flanges 30 and 43 of saddle splines 20 and 40, respectively of sections A, C and E bear on the corresponding support splines 19 of sections B and D, and hooks 23 at the ends of the cross beam support splines 19 of sections B and D bear on main beams 10, whereby all of the panel sections are supported by main support members 10. Note that the ends of flanges 22 and 29 of support and saddle splines 19 and 20, respectively, and the ends of flanges 42 of saddle splines 40 are inwardly spaced from the corresponding flanges 17 and 18 of main support members 10.

The foregoing assembly is continuous throughout the ceiling structure and, with the interlocking of the support member flanges in the associate kerfs of panels 13, there is provided a rigid, integral ceiling barrier between a room and the space above.

Access panel 14 may be located at any desired position in the suspended ceiling in place of any panel section having saddle splines on its lateral edges and comprises generally a pair of panel segments 37 and 38 extending in end to end relation between main support members 10. Each panel segment 37, 38 includes a pair of saddle splines 40 along its opposite lateral edges for hooking over respective support splines 19 on adjacent panel sections B, D. Saddle splines 40 are similar in cross section to saddle splines 20 and comprise a web portion 41, a lower horizontal flange 42 and a downwardly inclined flange 43 surmounting web 41 on the side thereof opposite flange 42. Saddle splines 40 extend along only their associated panel segments 37, 38. With this arrangement, it is seen that panel segments 37 and 38 are free to pivot upwardly about their remote ends (adjacent main beams 10) on axes indicated at 44 in FIG. 2 passing through the juncture of the remote ends of the inclined flanges 43 of saddle splines 40 and the ends of webs 21 of support splines 19. The end edges of inclined flanges 43 abut legs 24 of hooks 23 preventing transverse displacement of panel segments 37 and 38 and, in the access panel closed position (FIG. 2), the inner, adjacent ends of saddle splines 40 are spaced from each other. During opening movement of segments 37 and 38 kerfs 33 are withdrawn from engagement about associated flanges 17 and 18 of main support members 10, there being sufficient clearance between the inner ends of saddle splines 40 and between flanges 17 and 18 and the upper and lower lips 34 and 35 of associated panels 13 to provide for free pivoting movement of the segments about their axes 44 as illustrated in FIGS. 1 and 4.

It is a particular feature of our invention that access panels 13 and 14 can be positively locked against such

upward opening, while being readily unlocked from below when access is desired. To this end, a locking connector generally designated 45 is provided between the adjacent ends of panel segments 37 and 38 to releasably hold down access panels 37, 38 in integral, flush relation with adjacent ceiling panels. Locking connector 45 includes a pair of saddle splines 46 similar to splines 20 and 40, each having a horizontal lower flange 47 slidably mounted in the kerf of the inner end panel 13 of segment 37 and a downwardly inclined upper flange 48 for hooking over the upper end of a half coped spline 50 having a horizontal flange 51 mounted in kerf 33 of panel 13 on the adjacent end of segment 38. Each locking saddle spline 46 has a stepped tongue 52 projecting longitudinally from its ends providing an end tab 53 and a pair of longitudinally spaced shoulders 54 and 55 at each end. Openings 56 are formed through the webs 21 of cross beams 11' in alignment with locking splines 46 whereby the latter can be slid toward the adjacent cross beam support splines 19 to engage tabs 53 in their respective openings 56 and thereby lock panel segments 37 and 38 in closed position flush with the adjacent panels to provide a smooth, continuous and uninterrupted suspended ceiling.

It will be appreciated that the engagement of the inclined flanges 48 of locking splines 46 over half coped spline 50 on segment 38 will hold down the latter, as seen in FIG. 2 and that, upon engagement of the foregoing locking arrangement, neither segment 37 nor 38 of access panel 14 can be moved upwardly without first retracting tabs 53 from openings 56.

It is a significant feature of this invention that locking connector 45, while located out of sight above access panel 14, is operable from below the suspended ceiling to both lock and unlock the access panels 14 whereby the decor and ornamentation provided by the ceiling is uninterrupted. To lock access panel 14 in place from below the suspended ceiling, a screwdriver or like tool is inserted between the adjacent panels 13 of segments 37 and 38 to engage behind shoulder 54 or 55 of either one of the locking splines 46, between the latter. The tool then is moved along in the space between the panels 13 to slide the engaged locking spline 46 toward the associated cross support member 11' to engage tab 53 in the corresponding opening 56. Tab 53 of the other locking spline 46 is similarly slid into its engagement with associated opening 56. As seen in FIG. 2, there is a slight clearance between adjacent panels 13 throughout the entire ceiling, and with shoulders 54 and 55 of web portions 57 (FIG. 4) of locking splines 46 in vertical registry above the clearance space between the adjacent panels 13 of segments 37 and 38, it is apparent that splines 46 can be engaged and access panel 14 locked in position in this manner without changes in the decor or ornamentation of its undersurface distinguishing it from the surmounting ceiling.

To release locking splines 46 from below, a screwdriver or the tool is inserted between adjacent panels 13 of segments 37 and 38 as before, to engage shoulders 55 on the ends of splines 46 adjacent cross beams 11' and slidably retract locking splines 46 toward each other. Tabs 53 are thereby withdrawn from engagement in their respective cross beam openings 56. As noted previously, the inner ends of saddle splines 40 are spaced apart, providing clearance between shoulders 55 and the associated webs 21 of support splines 20 into which the tool can be inserted. Segments 37 and 38, when thus freed of interlocking connection with their adjacent panel sections, can be pivoted upwardly by pushing from below thereby providing access into the space between the suspended ceiling and the overhead supporting structure.

Where fireproof panels are utilized, ceiling integrity can be maintained throughout even in the event of a fire. Note that legs 24 of hooks 23 and flanges 22 and 29 are spaced inwardly from main support 10 and that flanges 22 are slidable on their associated kerfs. In this

manner, cross members 11 and 11' can expand lengthwise toward main support members 10 without destroying the integrity of the ceiling.

It is thus apparent that the objects of my invention have been fulfilled. The decor of the suspended ceiling is uninterrupted by the access panel and the integrity of the ceiling is maintained with the access panel in locked position. When access is desired, the access panel is readily unlocked from below the ceiling easily opened by pushing upwardly thereagainst.

Having thus described and illustrated one preferred form, of our invention, it will be understood that such description and illustration is by way of example only and that such modifications and changes as may suggest themselves to those skilled in the art are intended to fall within the scope of the present invention as limited only by the appended claims.

We claim:

1. In a suspended ceiling having a grid system supporting a plurality of closely spaced ceiling panels including an access panel, wherein said grid system includes a pair of spaced parallel support members extending along opposite sides of said access panel and means supporting said access panel adjacent one end thereof for pivotal movement about an axis normal to said members between an open position providing access through said ceiling and a closed position in which said access panel is substantially coplanar with adjacent ceiling panels with the edges of said access panel in closely spaced relation to the edges of said adjacent panels to provide a substantially continuous exposed ceiling surface, releasable locking means located in their entirety above said exposed ceiling surface locking said access panel in said closed position, said locking means including a locking member engaging said access panel adjacent the opposite end thereof and movable relative thereto along an axis parallel to said pivot axis into and out of locking engagement with one of said support members, said locking member being accessible from below said ceiling surface to release said access panel for movement to said open position, said support members including relatively fixed support spline members and saddle spline members carried by said access panel on opposite sides thereof for movement therewith, said saddle spline members engaging said support spline members for supporting said access panel against movement downwardly below said ceiling.

2. A suspended ceiling according to claim 1 wherein said access panel and an adjacent panel have a clearance slot therebetween, said locking member lying in substantially vertical registry with said slot and having shoulder means engageable through said slot from below said ceiling for sliding said locking member into and out of locking relation between said access panel and said grid system.

3. A suspended ceiling according to claim 2 wherein said locking member has first and second shoulders engageable through said slot from below said ceiling when said access panel is in said closed position to extend and retract said locking member into and out of said locking relation.

4. A suspended ceiling according to claim 1 wherein said one support member has a lock part, said other end of said access panel lies in close juxtaposition to another ceiling panel providing a clearance slot therebetween, said locking member lying in substantially vertical registry with said slot and having a locking tab, said locking member being engageable through said slot from below said ceiling surface for sliding along said access panel to engage said tab with said lock part.

5. A suspended ceiling structure as in claim 1, wherein there are a pair of said locking members engaging said access panel and movable into and out of engagement with both of said support members.

6. In a suspended ceiling having a grid system support-

ing a plurality of closely spaced ceiling panels including an access panel, wherein said grid system includes a pair of spaced parallel support members extending along opposite sides of said access panel, said access panel comprising a pair of panel segments lying in end-to-end relation, said grid system including means supporting said panel segments adjacent the remote ends thereof for pivotal movement about substantially parallel axes normal to said members between an open position providing access through said ceiling and a closed position in which said access panel segments are substantially coplanar with adjacent ceiling panels with the edges of said access panel in closely spaced relation to the edges of said adjacent panels to provide a substantially continuous exposed ceiling surface, releasable locking means located in their entirety above said exposed ceiling surface locking said access panel segments in said closed position, said locking means including a locking member between said panel segments engaging the adjacent end of one of said segments and movable relative thereto along an axis parallel to said pivot axes into and out of locking engagement with one of said support members, said locking member being accessible from below said ceiling surface to release said access panel segments for movement to said open position, said support members including relatively fixed support spline members and saddle spline members carried by the other of said access panel segments on opposite sides thereof for movement therewith, said saddle spline members engaging said support spline members for supporting said other access panel segment against movement downwardly below said ceiling, a spline member positioned between said access panel segments and engaging the adjacent end of said other segment, said locking member engaging said last-named spline member for supporting said one access panel segment against movement downwardly below said ceiling and for holding said other segment against opening movement when said locking member is in locking engagement with said one support member.

7. A suspended ceiling according to claim 6 wherein the adjacent ends of said segments lie in close juxtaposition providing a clearance slot therebetween, said locking member lying in substantially vertical registry with said slot and being engageable through said slot from below said access panel for sliding along said segments into and out of locking engagement with said grid member.

8. A suspended ceiling according to claim 7, one of said supporting members having a lock part, said locking member having a locking tab and a shoulder, said shoulder being engageable through said slot from below said access panel to slide said locking tab into and out of engagement with said lock part.

9. A suspended ceiling according to claim 6, wherein said panel segments are freely movable upwardly from below upon movement of said locking member out of locking engagement with said grid member.

10. In a suspended ceiling having a grid system supporting a plurality of closely spaced ceiling panels including an access panel, means supporting said access panel for movement between an open position providing access through said ceiling and a closed position in which said access panel is substantially coplanar with adjacent ceiling panels with the edges of said access panel in closely spaced relation to the edges of said adjacent panels to provide a substantially continuous exposed ceiling surface, releasable locking means located above said exposed ceiling surface locking said access panel in said closed position, said locking means being accessible from below said ceiling surface to release said access panel for movement to said open position, said grid system including a first pair of spaced parallel support members and a second pair of spaced parallel support members extending substantially normal to said first pair of members, said access panel comprising a pair of panel segments lying in end-to-end relation between said pairs of support mem-

bers and supported thereby for pivotal movement substantially about the lengthwise axes of said first support members, said panel segments having perimetrical grooves along the sides thereof, said first pair of support members having normally vertical web portions and normally horizontal flange portions loosely engaged in the grooves at opposite ends of said panel, said second support members each including a support spline extending between and engaging said first support members and a pair of saddle splines, said support splines each having a normally vertical web portion and a normally horizontal flange portion extending away from said access panel for engaging other panels, said saddle splines each having a normally vertical web portion, an inclined flange portion engaging over the web portion of the adjacent support spline, and a normally horizontal flange portion engaging the grooved side of the adjacent panel segment, each of said support splines having an opening through the web thereof between the associated pair of saddle splines, a pair of locking saddle splines and a half-coped spline between said panel segments, said half-coped spline having a normally vertical web portion and a normally horizontal flange portion engaged in the adjacent grooved side of one of said panel segments, said locking saddle splines

each having a normally vertical web, an inclined flange engaging over the web of said half-coped spline, and a normally horizontal flange engaging the adjacent grooved side of the other of said panel segments, said locking saddle splines having tabs at the outer ends thereof for engagement with said second support member openings and being slideable along said second support members, said locking saddle splines having shoulders adjacent the opposite ends thereof for engagement from below said panel through the space between said panel segments to slide said locking splines therealong.
